UNITED STATES PATENT OFFICE.

JULIUS ESCHWEGE, OF NEW YORK, N. Y.

DESIGN FOR A COMB FOR PERSONAL WEAR.

SPECIFICATION forming part of Design No. 31,521, dated September 19, 1899.

Application filed August 5, 1899. Serial No. 726,326. Term of patent 3½ years.

To all whom it may concern:

Be it known that I, JULIUS ESCHWEGE, a citizen of the United States, residing in the city of New York, borough of Manhattan, State of New York, (post-office address at No. 598 Broadway, in said city,) have invented and produced a new and original Design for a Comb or the Like, of which the following is a specification.

10 Reference is had to the accompanying drawings, forming part of this specification, in which—

15 The leading or material feature of my design consists of the segmental frame-like portions 1, having the inwardly-extending prongs 2, each frame-like portion having at the top

the interlocking curved extensions 3 4 and the outwardly-extending wing-like portions 5, 20 projecting from the frame-like portions 1 intermediate of the top and bottom thereof on a curved line, the outer ends 6 of the wings being disposed transversely to the plane of the inner ends 7, as shown in Fig. 2. 25

Having described my invention, what I claim as new, and desire to obtain by Letters Patent, is—

The design for a comb, for personal wear, substantially as herein shown and described. 30

Signed at the city, county, and State of New York this 4th day of August, 1899.

JULIUS ESCHWEGE.
